UNITED STATES PATENT OFFICE.

JOSEPH E. DRAKE, OF BLUE RAPIDS, KANSAS.

GRAIN-CAR DOOR.

Application filed March 8, 1923. Serial No. 623,800.

To all whom it may concern:

Be it known that I, JOSEPH E. DRAKE, a citizen of the United States of America, and a resident of Blue Rapids, in the county 5 of Marshall and State of Kansas, have invented a new and Improved Grain-Car Door, of which the following is a description.

My present invention is designed more 10 particularly as an improvement on the grain car door forming the subject matter of my Patent Number 1,450,842, granted April 23, 1923, and an application filed by me September 14, 1922, Serial Number 588,193.

15 The invention forming the subject matter of the patent and application referred to comprises an assemblage including a main built-in car door and an auxiliary door at the bottom of the main door.

20 The present invention is characterized by a novel auxiliary door and its appurtenances and the general object of the invention is to provide an auxiliary door having novel means for engaging the main door and 25 maintaining the auxiliary door in position while bracing the main door as well as to provide on the auxiliary door novel means to receive a bar or lever for working the auxiliary door loose for the discharge of 30 the contents of the car.

Reference is to be had to the accompanying drawings forming a part of this specification, it being understood that the drawings are merely illustrative of one example 35 of the invention.

Figure 1 is an exterior view of a grain car door embodying my invention showing the same emplaced;

Figure 2 is a view showing the auxiliary 40 door in plan and with an end thereof in horizontal section and showing a portion of the car body in horizontal section on line 2-2, Figure 1;

Figure 3 is a face view of one of the 45 bar sections appurtenant to the auxiliary door and having supporting and bracing relation to the main door;

Figure 4 is a transverse vertical section on the line 4-4, Figure 1;

50 Figure 5 is a perspective view of a portion of the auxiliary door;

In carrying out my invention in accordance with the illustrated example my improved auxiliary door, designated generally by the numeral 10 has a width to be disposed in the usual door opening, 11, of a car 12 to overlap the sides of the door frame at the interior of the car, said auxiliary door being positioned at the bottom of the opening beneath the main door 13 which may be of any approved construction. In the auxiliary door 10 at each end is a series of recesses or depressions 14 extending from the face of said door and advantageously through plate 15 applied thereto, 65 said plate and the series of holes being oblique.

At the center of the auxiliary door 10 at the outside is a broad vertical slidable element 16, said element in the raised position overlapping the lower edge portion of main door 13. In element 16 is a vertical slot 17 through which a bolt 18 passes, the bolt passing also through horizontal strap 19 applied to the face of door 10. The 70 ends of the strap 19 are fastened in any suitable manner to vertical strengthening plates 20 applied to the door 10 inward from the ends thereof. Applied to door 10 also at the front are vertically disposed 75 angle pieces 21 which lie close to the sides of element 16 to guide the same.

At the top of door 20 I provide, as in my previous constructions referred to, bar sections 22 having studs 23 to be taken hold 80 of in manipulating said bar sections lengthwise. The bar sections are accommodated in a longitudinal rabbet 110 at the top of door 10 and lie behind the angle pieces 21 and plates 20. Transverse bolts 24 pass 85 through the plates 20 and through oblique slots 25 in bar sections 22 so that a longitudinal movement of the said bar sections will cause the same to move vertically by reason of the oblique slots and the bolts. On the 90 door 10 at the ends of the rabbet 110 are inclines 26 to be engaged by the outer ends of the bar sections 22. On the door 10 at the bottom of the rabbet 110 are produced vertical shoulders 27 and corresponding notches 122 are formed in the lower edges of the bar 22, see Figure 3, so that 100

said shoulders 27 constitute stops for the bar sections 22 in the lowered position of the latter.

In practice the door 10 is placed in the opening across the doorway at the bottom beneath the main door 13 at the inner side of the door frame and the element 16 and bar sections 22 are then raised to engage the main door after which the nuts 28 of bolts 24 and the nut 29 of bolt 18 are tightened, holding the auxiliary door 10 firmly in position. The raising of the bar section 22 causes the outer ends thereof to overlap the door frame whereas in the lowered position the said bar sections will clear the door frame. To remove the door 10 the bar sections 22 are lowered to disengage the ends from the door frame and a lever bar A is employed by entering the end thereof in that hole 14 of a series which is nearest to the adjacent door frame so that the lever A may be caused to move the door 10 endwise. The endwise movement of the door 10 is made progressive by engaging the lever bar A in successive recesses 14 until the said auxiliary door is clear of the main door frame, whereupon the auxiliary door may be readily moved outwardly.

In the present application the bar sections (22) are not claimed broadly. The generic invention residing in said bar sections is claimed is an application filed by me September 14, 1922, Serial Number 588,193. The bar sections 22 having a length to overlap the door frame form no part of the present invention and are not incidental to the present invention. The said bar sections thus arranged to overlap the door frame form part of the invention forming the subject matter of an application filed September 14, 1922, and pending concurrently here-with.

The car is prepared for loading as follows: The auxiliary door 10 is placed in position as described and the bar sections 22 are moved to the raised position. Then the first ordinary grain door section is placed in position resting upon the sections 22 and said ordinary grain door section is then nailed solidly to the doorway post. Subsequently, the doorway is built up with rough doors as high as desirable. I would state that when the bar sections 22 are raised and the slide 16 moved to the raised position, the nuts 28 and 29 are tightened up.

When the car is unlocked and the door is to be taken out to discharge the cargo, the slide 16 and the bar sections 22 are lowered. The lever bar A is then employed to disengage the auxiliary door from the car frame to permit removal of said auxiliary door. The bar sections 22 are so formed and arranged as to overlap the door frame when the bar sections are raised and form part

of the invention claimed in the present application, the illustrated form in the present case lending itself particularly to the projection of the bar sections overlapping the door frame to a material extent.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. An auxiliary grain car door adapted to be emplaced in the doorway of a car beneath a main door, said auxiliary door having a longitudinal series of recesses at an end thereof adapted to receive the end of a lever for prying the auxiliary door endwise from its position in the doorway, the outermost recesses being adjacent the end of the auxiliary door whereby to be overlapped by the framework of the car and to be exposed in succession as the lever is successively engaged with the recesses.

2. An auxiliary grain car door adapted to be emplaced in the doorway of a car beneath a main door, said auxiliary door having an oblique longitudinal series of recesses at an end thereof adapted to receive the end of a lever for prying the auxiliary door endwise from its position in the doorway, the outermost recesses being adjacent the end of the auxiliary door whereby to be overlapped by the framework of the car and to be exposed in succession as the lever is successively engaged with the recesses.

3. An auxiliary door adapted to be placed in the door opening of a car beneath the main door, a vertically slid able element mounted on said door movable to or from a position projecting above said auxiliary door for overlapping at a main door, and bar sections at each side of said vertical element at the top of the door and movable vertically to engage the main door to temporarily support said main door until the latter is nailed fast, said bar sections having a length to be given a position overlapping the main door frame.

4. An auxiliary door adapted to be placed in a door opening of a car beneath the main car door, angle pieces on the door at the front and spaced from each other forming a vertical guideway, an element on the door slid able between said angle pieces, a strap extending across said angle pieces and across said element and having a slot and pin connection with said element to permit the vertical sliding of said element, said element being movable to a position to project above the auxiliary door to overlap the main door.

5. An auxiliary grain car door having a

longitudinal rabbet on the upper edge thereof, bar sections in said rabbet and formed with oblique slots, transverse bolts passing through said slots and through fixed parts of said auxiliary door, said bolts and slots adapted by a longitudinal movement of the bar sections to give a rising and lowering movement to said sections, inclines on the

auxiliary door at said rabbet on which inclines the outer ends of said bar sections 10 rest, and stop shoulders in said rabbet, said bar sections having notched portions to engage said stop shoulders in the lowered position of said bar sections.

JOSEPH E. DRAKE.
